(57) CLAIM

The ornamental design for a playing card caddy, as shown and described.

DESCRIPTION

FIG. 1 is a top, right side perspective view of the playing card caddy showing my new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The long dash-dash broken lines illustrates stitching in the fabric and forms part of the claimed design. The short dash-dash broken lines in FIGS. 1 and 2 illustrate portions of the playing card caddy and form no part of the claimed design. Any shading is not a feature of the design but is utilized to illustrate the surface contours of the playing card caddy in the drawings.
